UNITED STATES PATENT OFFICE.

OSCAR F. GRANLUND, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

DECORATING-DEPOSITOR.

1,268,003.

Specification of Letters Patent. Patented May 28, 1918.

Application filed January 8, 1916. Serial No. 70,975.

To all whom it may concern:

Be it known that I, OSCAR F. GRANLUND, a citizen of the United States of America, residing in the city of Springfield, county of 5 Hampden, and State of Massachusetts, have invented certain new and useful Improvements in Decorating-Depositors, of which the following is a specification.

This invention relates to an improvement 10 in decorating depositors which are used, for example to deposit chocolate or like pasty material in the form of a string and in various configurations on coated candies, or cakes, for the purpose of decoration. The 15 improvement comprises new means and devices for insuring the depositing of the string in a curved line with or without movement of the receptacle.

For a knowledge of the machine to which 20 this improvement is applied reference may be had to U. S. Letters Patent No. 1,208,328, granted Dec. 12, 1916 to Theodor Kihlgren. Only so much of the machine as is necessary for an understanding of my invention is 25 herein shown.

The invention embodies in its broad form the combination of a receptacle having an outlet, means to positively and continuously eject the material through the outlet including means to keep the outlet free from 30 clogging up, with means to change the position of the outlet with respect to the receptacle whereby the string ejected therefrom will be deposited in a curved line. One of 35 the preferred forms for this purpose embodies a receptacle having a rotatable plate in the bottom thereof, an outlet in the plate offset from the axis thereof, means to rotate the plate and agitating and expelling means 40 operable during the rotation of the plate to eject the decorating material in a string.

The objects of the invention will appear from the following detailed description and more particularly from the annexed claims.

45 For the purpose of illustration, a single embodiment of the invention is shown in the accompanying drawings, in which—

Figure 1 is a fragmentary longitudinal section showing the invention as applied to a 50 stringer;

Fig. 2 is a bottom plan view thereof; and

Fig. 3 is a detail sectional view drawn to an enlarged scale.

Referring to these drawings and particularly to Fig. 1, A represents a container for

the decorating material which container is adapted to be supported above a traveling belt carrying candies to be decorated. Within this member A, a chocolate tank a is formed, and at the bottom of the tank are 60 a series of cylindrical wells of a number equal to the number of rows of candies on the belt. Concentrically mounted in these wells a are double helical bladed sleeves 1 which are secured by the set screws shown, 65 to other sleeves 2. The latter are suitably journaled as shown in the upper portion of member A and have keyed thereto gears 3 which intermesh, forming a train. This gear train may be driven from any suitable source 70 of power in any desirable manner, and it has not been thought necessary to illustrate such connections as they are not essential to a full understanding of the invention.

Loosely mounted within the sleeves 2 are 75 rods 4 which extend upwardly above the container A and have an upper portion 5 of somewhat reduced diameter. Supported above the container A and in parallel relation therewith is a plate 6 which has 80 a depending boss having a hole 7 therein. Loosely fitting within the latter is a stud 8 which has a nut 9 thereon arranged to engage and support the lower face of the boss. Although only one of these supporting devices 85 is illustrated, it is to be understood that there is another similar device at the other end of the container. Loosely mounted on the portions 5 are sleeves 10, which have squared exterior surfaces 11 and lower 90 threaded portions 12 to engage in plate 6 as shown. The sleeves 10 are held axially by the flanges on spindles 4 and collars 13 and are arranged, when turned, to elevate the spindles 4 relatively to plate 6. Slidably 95 mounted on the squared portions 11 are gears 14 which intermesh, forming a train. These gears are arranged to be turned by hand vertically to adjust the spindles, and, obviously, one gear may be turned to adjust all 100 the spindles simultaneously or an individual gear may be moved upwardly out of mesh with its mating gears to adjust a single spindle without disturbing the others. The gear train is held in adjusted position by a 105 retractable stop 15.

Slidably keyed to an extension of one of the sleeves 2 is a ratchet 16 which is arranged to engage a pair of pawls 17 depending from plate 6. 18 and 19 are movable 110

and fixed coating cams arranged below the ratchet 16 and operative to raise the latter into engagement with the pawls 17 when desired. A spring 20 fixed to member A is arranged to act on a pin 21 normally to hold the plate 6 against stop 9. It is to be understood that a similar ratchet structure is provided at the other end of the container although only one has been illustrated. The 10 cam elements 18 and 19 are not shown in full detail as this device to raise and lower the ratchet 16 is the usual one and is well known in the art. The ratchet 16 thus provides a means for imparting a continuous and rapid vertical vibratory motion to plate 6 and all of the spindles 4.

Secured to the first and last screw 1 are sprockets 22 (one only being shown) which bear a chain 23, whereby the chocolate within the tank *a* is kept thoroughly stirred. The screw agitators 1 also assist in the thorough stirring of the chocolate and force the latter downwardly into the wells *b* to be expelled in a manner to be described.

25 Referring more particularly to Fig. 3, each well *b* is closed at the bottom by a circular plate 25 having gear teeth 26 in the periphery thereof. The gears thus formed intermesh in a train as best shown in Fig. 30 2, and this train may be driven by any suitable means (not shown). Each plate 25 has an annular groove therein which engages a corresponding flange 27 on the lower face of the container A, and the several gears are 35 held against these bearing flanges by a grid 28 secured as shown in Fig. 2 to the bottom of the container A.

Formed eccentrically in each plate 25 is a conical depression 30 having an outlet aperture at its lower end. Resting in the latter is a spindle 31 which has a tapered lower end. This spindle is rotatably supported in an upwardly extending offset arm 32 integrally formed with plate 25 and fixed to 40 the upper end of the spindle 31 is a pinion 33. The latter meshes with an annular gear 34 formed in the lower end of the bladed screw 1 whereby the rotative movement of the latter is transmitted to the spindle 32.

45 The rod 4, heretofore described, has its lower end bent and formed with a fork 35 which loosely engages the spindle 32 and supports the latter by bearing in under the flange of the pinion 33, as shown.

50 In operation, the chocolate in the vat *a* is forced downwardly by the revolving bladed screws 1. The spindles 31 are adjusted for a suitable opening by the threaded sleeves 10 already described, and these spindles are 55 constantly vibrated axially, whereby, in conjunction with the screws 1, the chocolate is positively expelled in a string. The gear connection 33 insures a constant rotative movement to keep the outlet 30 at all times 60 clear. As the chocolate is continuously ex-

65 pelled in string-like form, the plates 25 are continuously rotated, whereby the string is caused to move in a circular path relative to the container A. Thus, candies passing in under these outlets 30 on a conveyer may 70 be decorated with looped and other configurations involving circular movements. Obviously by varying the speed of the gears 26 and maintaining a uniform rate of travel for the conveyer, these configurations may 75 be varied as desired in a now well known manner. By providing a flexible drive for the gears 26 the receptacle may move at the same time the plates 25 rotate and thus the material may be laid in a large number of 80 variously decorative forms.

The invention may be carried out in other forms than the one herein specifically shown and described. The scope of the invention is pointed out in the annexed claims.

85

What I claim is:

1. A depositor for decorating purposes comprising a receptacle for chocolate and the like, a rotatable plate in the bottom thereof having an outlet offset from the axis 90 of the plate, agitating and expelling means arranged adjacent the outlet and adapted to continuously expel chocolate from the latter in the form of a string, and means to rotate said plate whereby said string may be 95 laid in a curved line.

2. A depositor for decorating purposes comprising a receptacle for chocolate and the like, means movable with respect to the axis of said receptacle and provided with 100 an outlet for the receptacle in the bottom portion thereof, and agitating and expelling means operable to positively and continuously eject chocolate through the outlet in the form of a string and driving devices for 105 said movable means.

3. A depositor for decorating purposes comprising a receptacle for chocolate and the like, a rotatable bottom portion for the receptacle provided with an outlet, a spindle in the latter arranged to eject chocolate therefrom, mechanism to revolve said spindle and said bottom portion, the outlet being arranged in offset relation to the axis of the 110 plate whereby the material issuing therefrom is laid in a curved line.

4. A depositor for decorating purposes comprising a receptacle, a series of rotatable disks arranged as bottom portions thereof each provided with an outlet opening offset 115 from its axis, agitating and expelling devices, one arranged adjacent each outlet opening, said devices including a vibratory spindle associated with each outlet and means to rotate said disks all constructed and arranged so that material from said receptacle may be positively expelled from 120 said outlets in the form of continuous strings and so that said strings may be laid in curved lines.

125

130

5. A depositor for decorating purposes comprising a receptacle, a series of rotatable disks arranged as bottom portions thereof each provided with an outlet opening offset 5 from its axis, agitating and expelling devices, one arranged adjacent each outlet opening, and means to rotate said disks together with means to move the agitating and expelling devices to maintain their relative positions with respect to said outlets whereby the material therefrom is laid in a curved line.
- 10 6. A decorating depositor, comprising, a receptacle for decorative material, a rotatable disk arranged to close the bottom of the receptacle and provided with an outlet offset from the axis of the disk, a spindle carried by the latter and associated with the outlet, means to continuously rotate said disk, 15 means to rotate said spindle relatively to
- 20 said disk, and means to vibrate said spindle in its outlet, all constructed and arranged so that material from said receptacle is positively expelled from the outlet in the form of a continuous string and so that the string may be laid in a curved line for decorative purposes.
- 25 7. A depositor for decorating purposes, comprising, a receptacle, a rotatable disk in the bottom thereof having an outlet offset 30 from the axis of the disk, an agitating and expelling device associated with said opening and movable in one direction relatively thereto, and means to rotate said disks together with means to move the agitating 35 and expelling device to maintain its relative position with respect to the outlet, whereby material issuing from the latter is laid in a curved line.

OSCAR F. GRANLUND.
